UNITED STATES PATENT OFFICE

HENRY BARTHOLDI, OF GENEVA, SWITZERLAND, ASSIGNOR TO THE EGRY REGISTER COMPANY, OF DAYTON, OHIO, A CORPORATION OF OHIO

AUTOGRAPHIC REGISTER

Application filed May 2, 1929, Serial No. 359,755, and in Switzerland June 18, 1928.

In machines for writing by hand rolls or pads of paper (printed if desired) are provided for receiving memoranda of business transactions, so that a set of copies of each inscription is obtained without manipulation of the carbon paper utilized, such as debits, credit notes, delivery notes, receipts, orders, etc., each of which is to be distributed to a different department for the preparation of, for example, accounts for clients and other parties of the preparation of statements.

The machine according to the invention, which utilizes rolls or packets of paper to receive the inscriptions and in which the said sheets are mechanically controlled to slide above a platen or writing table between fixed bands of carbon paper and beneath a cover plate forming a support, is characterized by the fact that there are provided on the lateral sides of the opening of the cover two openings facing one another for the introduction beneath the said cover of supplementary sheets larger than the said opening, the said cover being interiorly provided with a guide arrangement and spring clamps adapted to be actuated from outside and so constructed as to permit the securing on the table of the supplementary sheet or sheets introduced beneath the cover.

This machine may be utilized, for example, for providing, at a single inscription, a detailed account for the client, the monthly detailed total of the account, the detailed debits, credit notes or receipts and, if desired, a delivery note or one or more record copies for the preparation of a general account or a numerical or alphabetical classification.

In the drawings accompanying this specification,

Fig. 1 is a perspective view, broken away, of the lid of a machine embodying the features of the present invention, said lid being shown in raised position;

Fig. 2 is a perspective view of the assembled machine showing the same in condition for operation;

Figs. 3 and 4 are broken away perspective views respectively of the opposite edges of

the lid, on a larger scale, and illustrating the clamping devices and their operating mechanism;

Fig. 5 is a broken away perspective view showing the means for operating the clamp- 55 ing means; and

Fig. 6 is also a perspective broken away view illustrating the connecting means between the sliding members at opposite sides of the lid or cover plate. 60

The drawings show, by way of example, one form of construction of the machine, which comprises a box or housing B carrying a table X in the well known manner. Fig. 1 shows the cover plate A' for the 65 housing, with which plate the invention particularly has to do. It will be seen that this cover A' is cut out at its upper portion thereby forming a large opening through which, when the plate is in position on the 70 housing, the table X is exposed, said opening communicating with two laterally extending supplementary openings or recesses F and F'. The plate A' is provided with two guide plates G, G' connected for simultaneous 75 movement by a lever H pivoted at I on the plate A'. The ends of this lever are provided with guide slots J, J' engaging pins K, K', fixed in bent portions of the guides G, G'. The said guides G, G' end in projections L, L' secured thereto and acting on clamps M, M' supported on the plate A' by springs N, N' secured to the latter by rivets R, R'. To the guide G' is fixed a button O, Figure 6, which traverses the plate A' 80 through a guide slot P in the said plate. The other guide G is provided with a groove Q in which is engaged a guiding and supporting rivet Z secured to the plate A'. Finally, the two guides are movable at their 85 lower ends in short guide members S, S' secured to the plate A'.

When the button O is pushed to the upper end of the slot P the projections L, L' of the bars G, G' set in movement thereby become 95 engaged under the clamps M, M' which are raised for the whole of their width.

The cover A' being secured to the body of the machine, the button O is raised as mentioned in the preceding paragraph and the 100

clamps M, M' then press against the writing table X which has an appropriate height for receiving the pressure of said clamps. The latter are roughened or milled in order to provide a "gripping" surface for retaining the paper in position to be operated upon. Fig. 2 shows in perspective the registering machine with its cover A' in position thereon. There is shown a double sheet T containing a sheet T' of carbon paper placed in the machine across the openings F, F' exactly above the printed documents and the carbons contained in the machine for receiving the same inscription as that made on the double sheet. When the button O has been pushed to the top of the slot P and the guide bars have been operated it will be seen that one projection L lowers the clamp M, thus causing pressure on the double sheet and holding it fixed on the plate X. The other projection, not shown in the figure, causes the same pressure and the double sheet can not be moved during writing.

It should be noted that the sheet T is engaged a considerable distance within the opening F and only a small distance in F'. In this position only the "doit" column of the double sheet is visible, thus indicating that a debit is to be written. If, on the contrary, the sheet is engaged to a considerable distance within the opening F' and only a small distance within F, the "avoir" column will be uncovered, so that the machine is then ready to receive a credit inscription.

The edges U, U' (Figs. 3 and 4) of the lateral openings F, F' facilitate sliding of the independent sheets on the machine, while the edges U'' and U''' of the clamps offer the minimum resistance to sliding. The cover is provided with marks V, V' corresponding to the first line of the sheet and to the first line of each of the copies placed on the writing table X and between the carbons by rotating the handle D.

When the sheet is double and contains a sheet of carbon paper the inscription is of course, made on the second sheet. Moreover, for each individual inscription made the same inscription is obtained on the various documents, debits, delivery notes, credit notes, receipts, files, pages of ledgers, etc., placed under the double sheet on the writing table of the machine and between the fixed sheets of carbon paper.

What I claim is:—

1. A writing machine comprising a casing, an apertured cover therefor, means for supporting recording paper beneath the aperture in the cover, clamping means within the frame for securing supplementary sheets of paper introduced through the aperture in the cover, and means for operating said clamping means from the exterior of the casing.

2. A writing machine comprising a casing, a cover therefor having a main aperture communicating with a pair of laterally extending recesses, means for supporting recording paper beneath the aperture in the cover, and means for clamping supplementary sheets of paper in exposed position in said main aperture and with their edges projecting into said recesses.

3. A writing machine comprising a frame, an apertured cover therefor, means for supporting recording paper beneath the aperture in the cover, clamping devices for securing sheets of paper during writing, and a pair of sliding bars within the casing and operable exteriorly thereof for actuation of the clamps.

4. A writing machine comprising a casing, an apertured cover therefor, means for supporting recording paper beneath the aperture in the cover, clamps for securing the sheets of paper during writing, an actuating bar for each of said clamps within the casing, said bars being interconnected by a lever pivoted to the cover.

5. A machine as claimed in claim 4, and including a button extending through the cover and engaging one of said bars for operating the same.

6. A writing machine comprising a casing, an apertured cover therefor, means for supporting recording paper beneath the aperture in said cover, said aperture being so formed as to permit insertion into the machine of sheets of paper of greater width than the main portion of the aperture, means for clamping such sheets at opposite sides of said aperture, an actuating bar for each of the clamping means, and a slotted lever pivotally connected to both of said bars for actuating the same in unison.

7. A writing machine comprising a casing, an apertured cover therefor, the aperture of the cover being extended by two supplementary recesses at one end thereof to allow insertion of sheets of paper, means for supporting recording paper beneath said aperture, clamps for securing the inserted sheets, and slide bars for actuating said clamps, the bars being interconnected by a lever pivoted to the cover and one of said bars carrying a pin extending through said cover for operation of the clamps.

8. A machine as claimed in claim 7, having bars bent intermediate their ends, a pin being secured in each bent portion to engage a slotted end of the connecting lever.

In testimony whereof I have signed my name to this specification.

HENRY BARTHOLDI.
